UNITED STATES PATENT OFFICE.

JOSEPH WILLIAM VALIANT, OF BALTIMORE, MARYLAND, ASSIGNOR OF ONE-HALF TO JAMES WESLEY HARVEY, OF SAME PLACE.

DESIGN FOR A DUST-PAN.

SPECIFICATION forming part of Design No. 25,079, dated January 21, 1896.

Application filed November 19, 1895. Serial No. 569,472. Term of patent 14 years.

To all whom it may concern:

Be it known that I, JOSEPH WILLIAM VALIANT, a citizen of the United States, residing at Baltimore, in the State of Maryland, have invented and produced a certain new and original Design for Dust-Pans, of which the following is a full, clear, and exact description.

My design consists of a dust-pan having at the rear an angular flat bottom arranged in substantially the same horizontal plane as the front edge of the blade of the pan, and having a curved or domed top elevated above the blade of the pan, the blade of the pan sloping from its front edge upwardly to the rear.

In the accompanying drawings, illustrating my design, in the two figures of which like parts are similarly designated, Figure 1 is a perspective view, and Fig. 2 is a longitudinal section.

The pan-blade *a* is corrugated or beaded longitudinally, as at *b*, and has the upright

sides *c*. The blade and its sides have at their rear an angular flat bottom *e* arranged in the plane of the front edge of the blade and a curved or domed top *f*, and the blade *a* inclines upwardly and rearwardly from its front edge. The flat bottom *e* and domed top *f* extend the width of the blade. *g* is the handle, arranged at the back of the pan.

The leading feature of my design comprises the parts *e* and *f*, and with this statement it is obvious that my design is not limited to the character of pan-blade, sides and handle.

What I claim is—

The design for a dust pan, substantially as described.

In testimony whereof I have hereunto set my hand this 2d day of October, A. D. 1895.

JOSEPH WILLIAM VALIANT.
